Des. 197,245
Patented Dec. 31, 1963

197,245

CHILD'S FOOD PLATE OR SIMILAR ARTICLE

John P. Bateson, 10 Welch Road, Lexington, Mass.

Filed July 31, 1963, Ser. No. 76,051

Term of patent 14 years

(Cl. D44—10)

FIG. 1

FIG. 2

FIG. 3

FIG. 4

FIG. 5

I claim:

The ornamental design for a child's food plate or similar article, as shown.
